UNITED STATES PATENT OFFICE

ROY LEO GOEBEL, OF WACO, TEXAS

MAGAZINE PENCIL

Application filed July 28, 1930. Serial No. 471,252.

This invention appertains to the type of pencils including a magazine for containing a number of leads, means for successively feeding the leads into usable position, and a 5 plunger mechanism for advancing or withdrawing the lead, as desired.

The invention provides a novel form and arrangement of magazine for the leads, a receiving chamber intermediate the magazine 10 and pencil opening and in communication with each, a feeder in the receiving chamber adapted to be operated manually or automatically, and a screw actuated plunger for moving the lead in the pencil opening and 15 actuated, if desired, to actuate the feeder.

While the drawings illustrate a preferred embodiment of the invention, it is to be understood that in adapting the means to meet specific needs and requirements, the design 20 may be varied and changes in the minor details of construction may be resorted to within the scope of the invention as claimed, without departing from the spirit thereof.

For a full understanding of the invention 25 and the merits thereof, reference is to be had to the following description and the drawings hereto attached, in which:

Figure 1 is a perspective view of a magazine pencil embodying the invention, the 30 cap being omitted and parts broken away.

Figure 2 is a view similar to Figure 1, showing the plunger and feeder elevated.

Figure 3 is an enlarged detail sectional 35 view on the line 3—3 of Figure 1.

Figure 4 is a detail sectional view of the upper part of the pencil with the cap in place.

Corresponding and like parts are referred 40 to in the following description and designated in the several views of the drawings by like reference characters.

The pencil comprises a holder in which is 45 provided the magazine, the receiving chamber, and opening for the passage of the leads. The pencil holder includes a core 1 and casting 2, the latter being preferably of metal whereas the core 1 may be of any suitable material best adapted for the purpose. The 50 pencil opening 3 is disposed axially of the holder and constitutes a passage for the

leads 4. A magazine 5 is formed at the butt end of the holder and is adapted to receive a number of leads 4. The bottom 6 of the magazine 5 inclines throughout its length to automatically direct the leads 4 toward the delivery end of the magazine. The receiving chamber 7 is disposed intermediate the pencil opening 3 and the magazine 5 and is in communication with each to receive a lead from the magazine and to deliver said lead to the pencil opening 3. A guide 8 communicates with the delivery end of the magazine 5 and is in line with the receiving chamber 7. The guide 8 consists of a short tube having a side portion cut away to form a tapering 65 wall which is presented to the pencil opening. The upper end of the guide 8 is flush with the inclined bottom 6 of the magazine so as not to obstruct the movement of the leads 4. A slot 9 leads outwardly from the receiving chamber 7 and receives a pin 10 projecting laterally from the feeder and forming a finger piece. An opening extends from the lower end of the receiving chamber 7 and its outer wall 11 is inclined for the lower end 12 70 of the feeder to ride upon. The outer wall of the receiving chamber 7 is depressed, as indicated at 13, and this depression is curved and coacts with a curved portion 14 of the feeder to effect lateral movement of the latter 75 as the feeder moves upwardly in the chamber 7. The inner side of the chamber 7 is in communication throughout its length with the pencil opening 3 to provide an unobstructed 80 passage of the leads from the chamber 7 into the opening 3.

The feeder includes a tubular sleeve 15 and a spring leg 16, which is curved in its length, as indicated at 14, and has its lower end inclined as shown at 12. A lip 17 projects laterally from the upper end of the tubular sleeve 15 and constitutes a stop to be engaged by the plunger for automatic operation of the feeder. Turning of the feeder is prevented 90 by the finger piece 10 operating in the slot 9. The tubular sleeve 15 is slidable on the guide 8 and is retained in place thereby. Normally, the feeder occupies a position with its leg against the outer wall of the chamber 7. 95 The plunger 18 operates in the opening 3 100

and its upper end 19 is angular and its intermediate portion 20 threaded to match the threads of a sleeve 21 fixed in the upper portion of the opening 3. A clip 22 at the lower end of the plunger 18 is adapted to grip the lead 4 occupying the opening 3. Longitudinal movement of the plunger 18 projects or withdraws the lead in a manner well understood in the use of automatic pencils.

10 5 An opening 23 is formed in the butt of the holder in line with the receiving end of the magazine 5. The leads 4 are supplied to the magazine 5 through the opening 23.

15 15 A cap 24 is snugly fitted upon the butt portion of the holder and is provided with a centrally disposed tube 25 which extends some distance into the upper part of the opening 3. The opening of the tube 25 corresponds to the non-circular portion 19 of the plunger which obtains a snug fit therein to enable rotation of the plunger upon turning the cap 24 to the right or to the left. A pencil eraser 26 is fitted to the cap 24.

20 25 Upon removal of the cap 24 from the holder, leads 4 may be supplied to the magazine 5 through the opening 23. The leads 4 gravitate toward the lower end of the magazine and enter the guide 8 in succession and pass through the tubular sleeve 15 into the receiving chamber 7. The plunger 18 is moved upwardly in the opening 3 and when the clip 22 engages the lip 17 the feeder is drawn upwardly. During the upward movement of the feeder, the guide 8 is contracted by the sleeve 15 to hold the lead engaged therein in an elevated position and the curved portion 14 of the spring leg 16 rides upon the curved wall of the recess 13 and the inclined end 12 rides upon the inclined wall 11 with the result that the spring leg of the feeder is moved laterally and displaces the lower lead from the receiving chamber 7. The lead thus displaced enters the opening 3 and is moved 30 35 40 45 50 55 through the latter to a position for use by means of the plunger which is advanced by rotating it through the instrumentality of the cap 24. Pressure is then applied to the outer end of the stem or pin 10 to force the feeder downwardly toward the pointed end of the pencil, thereby permitting the spring leg 16 to assume a normal position close against the outer wall of the chamber 7. This permits of the next lead dropping into the receiving chamber 7 where it will be held since its upper end is engaged in the sleeve 15.

What is claimed is:

1. A magazine pencil comprising a holder having a centrally disposed pencil opening, a receiving chamber in communication with the pencil opening, and a magazine for receiving a number of leads, said magazine opening into the receiving chamber, a feeder in the receiving chamber and adapted to receive a limited longitudinal movement and

having a laterally movable portion, coacting means between a wall of the receiving chamber and the laterally movable part of the feeder to effect a positive lateral movement of said movable part to deliver a lead from the receiving chamber to the said pencil opening. 70

2. A magazine pencil comprising a holder having a centrally disposed pencil opening, a receiving chamber in communication with the pencil opening, and a magazine for receiving a number of leads, said magazine opening into the receiving chamber, a feeder in the receiving chamber and adapted to receive a limited longitudinal movement and having a laterally movable portion, coacting means between a wall of the receiving chamber and the laterally movable part of the feeder to effect a positive lateral movement of said movable part to deliver a lead from the receiving chamber to the said pencil opening, and a plunger movable in the pencil opening and adapted to engage said feeder 80 85 90 95 100 105 110 115 120 125 130

3. A magazine pencil comprising a holder provided with a centrally disposed pencil opening, a magazine for receiving a number of leads, and a receiving chamber in communication with said pencil opening, and with the magazine, a feeder in the receiving chamber and adapted to have a limited longitudinal movement therein, and comprising a receiver, and a spring leg, the latter having portions deflected, and the receiving chamber having a wall formed with depressed portions for the deflected parts of the spring leg to ride upon for moving said leg laterally to displace a lead from the receiving chamber and cause it to enter said pencil opening. 100

4. In a magazine pencil, a holder having a central pencil opening, a receiving chamber in communication with the pencil opening, and a magazine for receiving a number of leads, said magazine having an opening in its bottom, a guide fitted in the opening of the magazine bottom and extending into the receiving chamber, a feeder in the receiving chamber comprising a tubular receiver engaging the said guide and movable thereon, and a spring leg for displacing leads from the receiving chamber and causing them to enter the pencil opening, and a plunger in the pencil opening and adapted to engage and effect longitudinal movement of the feeder. 110 115 120 125 130

5. A magazine pencil comprising a holder provided with a central pencil opening, a receiving chamber in communication with the pencil opening, and a magazine having an inclined bottom in which is formed a discharge opening, a guide fitted in said discharge opening and having a side portion cut away, a feeder in the receiving chamber having a limited longitudinal movement therein and comprising a tubular receiver

and a spring leg, said receiver engaging the beforementioned guide and movable thereon and said spring leg having portions deflected laterally to coact with corresponding portions of the outer wall of the receiving chamber, and a plunger operable in the pencil opening and adapted to effect a longitudinal movement of the feeder.

6. A magazine pencil comprising a holder formed with a central pencil opening, a receiving chamber, and a magazine, there being an opening leading outwardly from the receiving chamber and the latter having its outer wall depressed and an opening leading from its lower end with its outer wall inclined, a feeder in the receiving chamber comprising a tubular receiver and a spring leg, the latter having an intermediate portion curved laterally and its ends and a finger piece projecting from the feeder and operable in the opening leading outwardly from the receiving chamber, and a plunger operable in the said pencil opening and adapted to engage and effect longitudinal movement of the feeder.

In testimony whereof I affix my signature.
